UNITED STATES PATENT OFFICE.

JOHN SANFORD SMALL, OF TOPEKA, KANSAS.

PAPER FILE.

Application filed November 17, 1924. Serial No. 750,225.

This invention relates to a paper file having novel means for the attachment of the sheets to their supporting means.

The invention will be best understood by reference to the following description, when taken in connection with the accompanying drawings of one illustrative embodiment thereof, while its scope will be more particularly pointed out in the appended claims.

10 In the drawings:

Fig. 1 is a front elevation of a portion of a paper file exemplifying the invention;

Fig. 2 is a sectional view on line 2—2 of Fig. 1 but with the card upstanding, the 15 better to illustrate the structure;

Figs. 3, 4, 5 and 6, are detail views illustrating various steps in the operation of assembling a sheet with its attaching means:

Fig. 7 is a perspective view of the attaching means;

Fig. 8 is a detail sectional view on line 8—8 of Fig. 2; and

Fig. 9 is a sectional view on line 9—9 of Fig. 8.

25 Referring to the drawings, and to the embodiment of the invention which is selected for illustration, there is shown a paper file comprising a series of sheets 10, herein having overlapped margins 11 to which identifying matter may be applied, thereby constituting an index for the file. Each sheet is associated with and supported by an appropriate support, such as a bar 12, which may be and herein is a flat, elongated strip 30 of metal which, in turn, is supported by a suitable support, which in the present embodiment is a panel-like tray 13, which may be in the nature of a sheet-metal drawer to be received in a cabinet not shown herein.

40 The panel or tray presents appropriate guides, such as channels 14, receiving the ends of the bars 12, the latter being parallel with and edge to edge with one another. Herein, for convenience of manufacture, the 45 channels 14 are presented by sheet-metal strips 15, suitably secured to the panel as by spot-welding the same thereto. The bars may be held in a somewhat elevated position that is to say, spaced from the back of the tray, by the provision of ribs 16 formed lengthwise of the strips. Removal of a given bar from and its replacement in the channels may be, and herein is, conveniently accomplished by making the bars flexible 50 and resilient, whereby they may be sprung or bowed to reduce their length to a distance

less than the space between the edge of one of a pair of flanges 17, and the bottom of the channel on the opposite side.

Each bar presents two aligned bearings 18, 60 extending lengthwise thereof, and herein conveniently presented by sheet-metal clips 19 (See Fig. 8), each having two arms 20 embracing the bar, bent towards each other on the bottom or back of the bar. The clips 65 are conveniently held against displacement lengthwise of the bar by providing the latter with lateral recesses or notches 21 (See Fig. 9), into which the arms are inserted, after which the ends of the arms are clenched by 70 bending them towards each other, and thus permanently uniting the clips with the bars. The bar, as previously noted, is elevated somewhat from the panel, and there is provided at least sufficient space for the inwardly bent ends of the arms of the bearing clips. 75

Each bearing receives a pivot or pintle, herein a piece of wire 22 (see Fig. 7), which is carried by a clip 23, formed of sheet metal having a wall 24 conveniently secured to the pintle by wrapping the former about the latter, as at 25, and squeezing the same sufficiently to provide a firm and permanent means of attachment. The wall 24 overlies 80 one face of the sheet 10, and is secured to the latter in a novel manner, which will now be described.

A second wall 26 overlies the opposite face of the sheet, and is connected to the wall 24 90 by an offset connecting portion 27, which is received in an opening, herein a slit 28 disposed lengthwise of the bar 12 and lengthwise of the adjacent edge of the sheet, there being two such slits in each sheet, one for each clip. The length of the slit is such that the offset portion of the clip is received snugly therein. Interlocking engagement of the clip and the sheet to prevent accidental detachment of one from the other is assured 95 by providing the wall 24 with an extension or projection 29, which extends lengthwise of and beyond one end of the slit, and the wall 26 may be and herein is provided with a similar extension or projection 30, which extends lengthwise of and beyond the other end of the slit. 100

Attachment of the clip to and detachment of the same from the sheet is accomplished by a rotary or gyratory motion, using the point of engagement of one end of the offset 27 with one end of the slit 28, as the center 110

or pivotal point for the swinging movement. This is rendered possible by making one end of the wall 26 oblique as at 31, so that a diagonal "A", which is a radius from the 5 pivotal point "B", shall be no greater, but preferably somewhat less, than the length of the slit 28.

The mode of attaching the clip to the card will now be described, reference being 10 had at first to Fig. 3, wherein the clip is shown placed flatwise against the sheet, with the pintle 22 disposed transversely of the slit 28. The clip is first moved in the direction of the arrow in Fig. 3, and the 15 projection 30 is caused to enter the slit, and the adjacent end of the offset 27 is caused to engage the adjacent end of the slit, as in Fig. 4. At or about this time, swinging movement of the clip in the 20 direction of the arrow in Fig. 5 about the pivotal point is begun, and is continued until the clip reaches its normal position represented in Fig. 6. Then, by squeezing the wall 26 towards the adjacent face of 25 the card, the offset 27 is caused to enter and snugly fit the slit. Detachment of the clip from the card can be accomplished by reversal of the foregoing operation.

For convenience of manufacture, both 30 clips for the card are made alike, and inasmuch as the pintles should point in opposite directions, it is evident that one clip has its wall 24 against one face of the card, and the other clip has its corresponding 35 wall against the opposite face of the card. This being so, it will be found most convenient to attach one clip, as in Figs. 3, 4, 5 and 6, and then turn the card over to present the other face uppermost to attach the 40 other clip.

In the present embodiment, the pintles can be inserted in their bearings only when the bar is detached from the panel, and then only when the bar is bowed or sprung 45 to reduce the distance between the bearings to less than the distance between the free ends of the pintles. The card having been attached to the bar, the latter can be inserted in its proper position in the panel by a 50 reversal of the operation of removing the same. With the parts thus assembled, detachment of the card cannot take place without first detaching the bar from the panel. Therefore, if the panel should be 55 dropped or carelessly handled, the cards cannot become accidentally detached therefrom. It should also be noted that the bars engage one another edge to edge throughout the entire length, there being 60 no lateral enlargements or spacing means whatever, the uniform width of the bar throughout its length being the means to determine the degree of overlap or exposure of the identification receiving margins of 65 the cards.

Having thus described one illustrative embodiment of the invention, but without limiting myself thereto, what I claim and desire by Letters Patent to secure is:

1. In a file, the combination of a sheet 70 having openings, attaching clips extending along one face of said sheet, thence through said openings and thence along the other face of said sheet, a frame, and a support detachable from said frame and affording 75 pivotal support for said clips on said frame and having means preventing removal of said sheet from said clips except by first removing said support from said frame.

2. In a file, the combination of a sheet 80 having openings, attaching clips extending along one face of said sheet, thence through said openings and thence along the other face of said sheet, a frame, and a support detachable from said frame and connecting 85 said clips to said frame, said support having means preventing detachment of said clips from said sheet while said support remains attached to said frame.

3. In a file, the combination of a sheet 90 having openings, attaching clips extending along one face of said sheet, thence through said openings and thence along the other face of said sheet, said clips having means to prevent their detachment from said sheet 95 except by rotative movement relatively to said sheet, and means affording support for said clips and preventing such movement.

4. In a file, the combination of a sheet having openings, attaching clips extending 100 along one face of said sheet, thence through said openings and thence along the other face of said sheet, said clips having means to prevent their detachment from said sheet except by rotative movement relatively to said sheet and parallel to the 105 plane of the latter, and means affording support for said clips and preventing such movement.

5. In a file, the combination of a sheet 110 having openings, attaching clips extending along one face of said sheet in one direction, thence through said openings, and thence along the other face of said sheet in the opposite direction, and means affording 115 pivotal support for said clips about an axis extending lengthwise of the adjacent edge of said sheet said clips being detachable from said means by movement lengthwise of said axis.

6. In a file, the combination of a sheet having openings, attaching clips extending along one face of said sheet in one direction, thence through said openings, and thence along the other face of said sheet in the opposite direction, means affording pivotal support for said clips, and means cooperating with such pivotal support, said clips and said sheet normally to prevent detachment of said clips from said sheet.

7. In a file, the combination of a sheet presenting openings, attaching clips extending through said openings and being removable therefrom by rotative movement, means affording pivotal support for said clips, and means cooperating with such pivotal support normally to prevent such rotative movement. 65
8. In a file, the combination of a sheet presenting openings, attaching clips extending through said openings and being removable therefrom by rotative movement generally parallel with the faces of said sheet, means affording pivotal support for said clips, and means cooperating with such pivotal support normally to prevent such rotative movement. 70
9. In a file, the combination of a sheet presenting openings adjacent one edge, U-shaped attaching clips extending across said edge, along one face of said sheet, thence through said openings, and thence along the other face of said sheet, and means affording pivotal support for said clips; the axis of said pivotal support extending lengthwise of said edge. 75
10. In a file, the combination of a sheet presenting elongated openings extending lengthwise of and adjacent one edge, U-shaped attaching clips extending across said edge, along one face of said sheet, thence through said openings, and thence along the other face of said sheet, and means affording pivotal support for said clips; the axis of said pivotal support extending lengthwise of said edge. 80
11. In a file, the combination of a sheet presenting elongated openings extending lengthwise of and adjacent one edge, attaching clips extending across said edge, along one face of said sheet, thence through said openings, and thence along the other face of said sheet, said clips presenting projections extending lengthwise of and beyond the ends of said openings, and means affording pivotal support for said clips. 85
12. In a file, the combination of a sheet presenting elongated openings extending lengthwise of and adjacent one edge, attaching clips extending across said edge, along one face of said sheet, thence through said openings, and thence along the other face of said sheet, said clips presenting each a projection extending lengthwise of and beyond one end of its opening, and means affording pivotal support for said clips. 90
13. In a file, the combination of a sheet presenting elongated openings extending lengthwise of and adjacent one edge, attaching clips extending across said edge, along one face of said sheet, thence through said openings, and thence along the other face of said sheet, said clips presenting each two projections extending in opposite directions lengthwise of and beyond the ends of its 95
- opening, and means affording pivotal support for said clips. 100
14. In a file, the combination of a sheet presenting openings, clips having walls embracing said sheet and connecting portions extending through said openings and presenting pivots about which said clips may be rotated to free them from said openings, and means affording pivotal support for said clips and normally preventing rotation about said pivots. 105
15. In a file, the combination of a sheet presenting openings, clips having walls embracing said sheet and extending along said sheet beyond said openings, said clips having also connecting portions extending through said openings and presenting pivots about which said clips may be rotated to free them from said openings, one wall of each clip having an oblique edge which swings through its opening about the pivot of such clip, and means affording support for said clips and normally preventing rotation about said pivots. 110
16. In a file, the combination of a sheet presenting openings, U-shaped clips extending across an edge of said sheet along one face of the latter, thence through said openings and thence along the opposite face of said sheet toward said edge, and hinge members presenting bearings and pivots affording pivotal support for said clips to turn about an axis extending lengthwise of said edge. 115
17. In a file, the combination of a sheet presenting openings adjacent one edge, attaching clips having walls overlying opposite faces, respectively, of said sheet and connecting portions extending through said openings, said walls having projections extending beyond said openings lengthwise of said edge, and means affording pivotal support for said clips. 120
18. In a file, the combination of a sheet presenting openings adjacent one edge, a flexible supporting bar, two hinges for said sheet, each comprising two separable hinge members one of which is an attaching clip having walls overlying opposite faces, respectively, of said sheet and a connecting portion extending through one of said openings, the other hinge member of each pair being attached to said bar, said hinges being so disposed as to prevent said connecting portions from being withdrawn from their respective openings without first flexing said bar and separating the two hinge members of one of said hinges. 125
19. In a file, the combination of a support, a series of parallel bars supported by said support; hinge members each comprising two aligned bearings extending lengthwise of said bar, pintles received in said bearings, respectively, and U-shaped sheet-sup-

porting clips carried by said pintles, respectively, each clip having two walls; extending toward said pintles and a series of sheets having overlapped margins, each sheet being associated with and held between the walls of one pair of clips and being provided with perforations in which said clips are snugly received and by which relative displacement of said clips and the associated sheet lengthwise of said pintles is prevented.

20. In a file, the combination of a support, a series of parallel bars supported by said support, hinge members each presenting two aligned bearings extending lengthwise thereof, pintles received in said bearings, respectively, U-shaped sheet-supporting clips carried by said pintles, respectively, each clip having two walls, and an intermediate connecting portion, and a series of sheets having overlapped margins, each sheet being associated with and held between the walls of one pair of clips and being provided with openings which snugly receive said intermediate connecting portions and prevent relative displacement of said clips and said sheet lengthwise of said pintles.

21. A filing element comprising, in combination, a sheet presenting an opening, and an attaching clip received in said opening, interlocked with said sheet against removal therefrom and having means rendering the same removable from said sheet only by swinging movement in a plane generally parallel with the plane of said sheet.

22. A filing element comprising, in combination, a sheet presenting an opening, and an attaching clip having a portion received in said opening and two portions on opposite faces of said sheet, said clip having means rendering the same removable from said sheet only by swinging movement in a plane generally parallel with the plane of said sheet.

23. A filing element comprising, in combination, a sheet presenting an elongated opening extending lengthwise of and adjacent one edge thereof, and an attaching clip having two walls overlying opposite faces, respectively, of said sheet and a connecting portion extending through said opening, one of said walls having a projecting portion extending lengthwise beyond one end of said opening.

24. A filing element comprising, in combination, a sheet presenting an elongated opening extending lengthwise of and adjacent one edge thereof, and an attaching clip having two walls overlying opposite faces, respectively, of said sheet and a connecting portion extending through said opening, one of said walls having a projecting portion extending lengthwise beyond

one end of said opening, and having one edge in alignment with a lengthwise edge of 65 said opening.

25. A filing element comprising, in combination, a sheet presenting an elongated opening extending lengthwise of and adjacent one edge thereof, and an attaching clip 70 having two walls overlying opposite faces, respectively, of said sheet and a connecting portion extending through said opening, one of said walls having a projecting portion 75 extending lengthwise beyond one end of said opening, and having one edge in alignment with a lengthwise edge of said opening, the opposite end of such wall having an edge which is oblique to said edge and slopes toward said projecting portion. 80

26. In a file, the combination of a support, a series of parallel bars disposed edge to edge and supported by said support, each bar presenting two pairs of oppositely disposed lateral notches, two clips associated with each bar and each having two arms embracing such bar and received in the notches of one pair, said arms being clinched over on the back of said bar between the latter and said support, and a series of sheets each associated with one of said bars and carried by its clips. 85

27. In a file, the combination of a support, a series of parallel bars disposed edge to edge and supported by said support, each bar presenting two pairs of oppositely disposed lateral notches, two clips associated with each bar and each having two arms embracing such bar and received in the notches of one pair, said arms being clinched over on the back of said bar between the latter and said support, each clip presenting an opening at the front of its associated bar, a series of sheets each associated with one of said bars, and means received in the openings of said clips of each bar and secured to the associated sheet. 100

28. In a file, the combination of a support, a series of parallel bars disposed edge to edge and supported by said support, each bar presenting two pairs of oppositely disposed lateral notches, two clips associated with each bar and each having two arms embracing such bar and received in the notches of one pair, said arms being clinched over on the back of said bar between the latter and said support, each clip presenting a bearing at the front of its associated bar, a series of sheets each associated with one of said bars, and means received in said bearings and securing each sheet to the bearings of its associated bar. 110

In testimony whereof, I have signed my name to this specification.

JOHN SANFORD SMALL.
